JOHN A. BROMAN, OF BERKELEY, CALIFORNIA.

INTERNAL-COMBUSTION ENGINE.

1,184,067.

Specification of Letters Patent. Patented May 23, 1916.

Application filed February 12, 1913. Serial No. 747,915.

To all whom it may concern:

Be it known that I, JOHN A. BROMAN, a citizen of the United States, and a resident of Berkeley, county of Alameda, and State of California, have invented new and useful Improvements in Internal-Combustion Engines, and more particularly in the valve mechanisms thereof, of which the following is a specification.

10 An object of the invention is to provide a simple valve action for this type of engine, suitable for the exacting requirements of marine service.

Another object is to so construct the valve action that all its parts are easily accessible, and so located and constructed that repairs can be easily and quickly made, when occasion demands. The adaptation of the crude oil or internal combustion type of engine to 20 marine work has been hampered by the construction of such engines, the principal disadvantage residing in the inaccessibility of many of the vital parts, such as the valve action and timing gear. A sea going craft 25 depends largely on headway for safety; it is, therefore, essential that its motive power be of such construction, that all parts may be easily accessible, quickly repairable and at all times open to inspection, to anticipate 30 so far as possible accidental stoppages.

The invention possesses other advantageous features that with the foregoing will be set forth at length in the following description, wherein I shall outline in full that 35 form of the invention selected for illustration in the drawings accompanying and forming part of the present specification. The novelty of the invention will be included in the claims succeeding said description.

40 From this it is apparent that I do not restrict myself to the disclosure made by said drawings and description as I may adopt many variations within the scope of my invention as expressed in said claims.

45 In the drawings: Figure 1 is a side elevation of a one-cylinder engine having this invention applied to the valve action thereof. Fig. 2 is a front elevation of the same. Fig. 3 is an enlarged view from above of the same.

50 Fig. 4 is an enlarged plan detail of the valve action and related portions of the engine, illustrating the engagement of the reverse air valve lifter.

In detail the construction consists of the 55 engine comprising the base 1, the crank

shaft 2, the cylinder 3, the piston 4, the fuel valve 5, the air valve 6, and the scavaging air valve 7 of the conventional type of crude oil engines.

The timing gear consists of the link 8 pivoted at 9 on the side of the piston 4 and at 10 to the end of the rocker arm 11, that is pivoted at 12 on the bracket 13 extended from the side of the engine. This rocker arm may be operated by an eccentric on the 60 crank shaft, or otherwise synchronized with the stroke of the piston. The push rod 14 is pivoted at 15 to the opposite end of the rocker arm, whereby the reciprocations of the piston are communicated to this push 70 rod. This push rod is guided in the oscillating guide sleeve 16, pivoted at 17 in the bracket 18 extended from the engine. As the piston rises on the compression stroke, the head 19 on the push rod forces the trip 75 20, fixed upon the valve shaft 21, backward. This valve is slidably mounted in the bearings 22-22 in the bracket 23 fixed upon the engine. This shaft is slidable within the sleeve 24 mounted thereon, between the bearings 22-22. This sleeve is provided with a slot 25 to engage the pin 26 fixed in the said shaft 21, whereby the oscillations of the valve shaft are communicated, through the arm 27, to the valve stem 28, pivoted at 29 80 thereto, to open and close the fuel valve 5, 85 the function of which is obvious.

To regulate the extent of the opening and closing of the fuel valve, the head 30 of the trip 20 is inclined across the axis of the 90 valve shaft, so that the distance that this trip is forced backward by the head 19 of the push rod depends upon the point at which the head 19 engages the inclined head 30. To control this action the valve rod is 95 provided with the annular groove 31, engaged by the yoke 32, on the end of the throttle lever 33, pivoted at 34 on the bracket 35, extended from the body of the engine. The throttle lever is provided with 100 the quadrant 36 having notches to engage the latch 37 attached to the lever and operated by the hand grip 38.

The scavaging valve 7 is operated by the 105 rocker arm 39, pivoted at 40 on the bracket 41 extended from the body of the engine. The opposite end of this arm engages the connecting link 42 pivoted in the arm 43, extended outwardly from the guide sleeve 16, the oscillations of which it communi- 110

ates to the said scavaging valve, whereby, after each stroke, as the piston approaches the end of the down stroke, the scavaging valve is opened and the products of combustion are exhausted from the cylinder through the ports 44, in the wall of the cylinder, and carried away through the exhaust manifold 45 surrounding the cylinder at this point.

10 Ignition may be accomplished in any suitable manner common to this type of engine.

Thus far has been described a crude oil engine capable of receiving, consuming and exhausting an adjustable quantity of fuel.

15 To reverse the rotation of the crank shaft means are provided for cutting off the fuel supply temporarily and running the engine on the auxiliary compressed air system after reversal, until sufficient momentum is attained to insure the continuance of the 20 reverse direction of rotation, before the fuel is again substituted for the compressed air source of power. The reversal interval disturbs the timing of the ignition moment 25 relative to the fuel admission; it is therefore advisable to run on compressed air as described, during this interval.

Reversal is accomplished by throwing the 30 throttle lever 33 into the position shown in Fig. 4; this throws the reverse valve lifter 46 into operative position. This lifter is preferably operated by the notched head 47 engaging the tapered lug 48 on the connecting link 42. The next stroke of the

35 piston, after the throttle has been set on the reverse is arrested by the compression in the cylinder (all valves being closed) and the piston rebounds in the opposite direction; at this instant the reverse lifter head 47 is 40 depressed by the down pull of the lug 48.

The gap 46' engaging the lug 53' on the bracket 53, gives the lifter a limited free oscillation on the valve shaft 21, see Fig. 3. The head 49 bears under the trip 50 spring 45 mounted in the head 51 on the stem 52, vertically guided in the bracket 53, mounted free upon the valve shaft 21 and guided against rotation by the rod 54, fixed in the bracket 23. The stem 52 is provided with

50 the lateral extension 55 having the yoke 56 within which the lever 57 is confined by the pin 58. The lever 57 is fixed upon the end of the rocker pivot 59, pivoted in the bracket 60 extended from the body of the engine. The opposite end of the pivot is provided with a valve tappet arm 61, adapted to open the spring closed compressed air valve 6, by pushing against the head 62 of the valve stem. Operating through the

55 above recited means, the air valve is opened by the upward push of the reverse valve lifter 46 at the proper time as determined by the placing of the lug 48. The succeeding up stroke of the connecting link 42 causes the inclined plane 63 on this lug to

rise out of the inclined notch in the head 47 and to push the notched head 47 laterally, shifting the valve shaft 21, permitting the latch 37 to be engaged with the notch R on the quadrant 36, which is the reverse position at slow speed. The head 19 in descending, forces the trip 50 back, against the tension of the spring 50', without depressing the bracket 53 or affecting the valve; but on the upstroke it engages under the trip, lifting it and the intervening mechanisms to open the air valve 6, to admit a charge of compressed air for each power stroke of the piston; the engine running on compressed air until proper timing of the ignition in the reverse direction takes place. The lever 57 is lifted by the push rod to a height determined by the distance from the fulcrum 59 that the yoke 56 controlled by the sliding valve shaft 21, engages the lever 57. The power of the engine, while running on air pressure, is controlled by the throttle lever 33 sliding the bracket 53 backward or forward. The trip 50 is sufficiently long to cover the range of 90 adjustments of the throttle lever with respect to this air valve 6. The closer the extension is to the pivoted point of the lever 57, the less the valve is affected, and vice versa. It is obvious that the engine can be 95 run on this compressed air valve mechanism as long as desired in either direction.

The fuel supply valve 5 closes when the 100 throttle lever 33 is shifted to the reverse position. When the engine has attained sufficient momentum in the reverse direction, under the successive impulses of compressed air, controlled by the air valve 6, the throttle lever is shifted to again throw the trip 20 into operation with the head 19 of the push rod, cutting in a charge of fuel through the fuel valve 5, as before described, the engine continuing to receive, consume and exhaust an adjustable quantity of fuel as normally in one direction of 105 crank shaft rotation, as in the other, with the possibilities of reversal in the manner described.

For the purpose of starting the engine from a standstill, the manual trip arm 66, 115 fixed on the rocker shaft 67, rotatable in the bracket 68 extended from the engine body, and the hand lever 69, fixed upon the rocker shaft is provided. The arm 66 extends beneath the extension 55 and lifts it to admit 120 the necessary quantity of compressed air into the cylinder, to throw the crank shaft into running position for the regular valve timing gear. In single cylinder engines, there might be positions at which the crank 125 would stop, and would not respond to pressure; in such a case it would be necessary to "throw it over the center" in the usual manner. In multicylinder engines, one crank pin would always be "off center" and that 130

piston would respond to any expansive force liberated within that cylinder. It will be apparent to a skilful operator how the manual valve control may be operated to 5 attain the desired operation of the engine in the proper direction of rotation.

While I have disclosed in the drawings and described a single cylinder engine and the preferred manner of putting this invention into practice thereon, and have not set forth the scope of modifications and equivalents of the specific mechanisms, I do not wish to be understood as confining myself to these particular disclosures, as the invention 10 may be variously applied and modified, to suit special types of single or multicylinder engines, upright or horizontal, without departing from the spirit of the invention set forth in the following claims.

20 I claim:

1. In an internal combustion engine, a valve mechanism including a pivotal valve shaft; a trip fixed upon said shaft and having a head inclined transversely to the axis 25 of said shaft; a push rod operated synchronously with the stroke of the engine, and engaging said inclined head; means for varying the point of engagement between said inclined head and the push rod; and a fuel valve operatively connected with said 30 valve shaft.

2. In an internal combustion engine, a valve mechanism including a pivotal valve shaft; a trip attached to said valve shaft 35 and inclined transversely thereto; a push rod operated synchronously with the stroke of the engine and engaging said inclined trip; means for varying the point of engagement between said trip and the push rod; a fuel valve operatively connected to said 40 valve shaft; and a scavaging valve operatively connected to said push rod.

3. In an internal combustion engine, a valve mechanism including a pivotal valve 45 shaft; a trip attached to said valve shaft and inclined transversely thereto; a push rod operated synchronously with the stroke of the engine and engaging said trip; means for sliding said valve shaft, to vary the 50 point of engagement between said trip and the push rod; a sleeve splined on said valve shaft and having an arm, a fuel valve engaging said arm; and a scavaging valve operated by said push rod.

55 4. In an internal combustion engine, a valve mechanism comprising a valve shaft, a valve trip fixed upon said shaft, a push rod engaging said trip, means for operating said push rod synchronously with the 60 stroke of the engine piston, means for sliding said valve shaft, an arm splined on said valve shaft and engaging the fuel valve of the engine, and an auxiliary air valve mechanism comprising a lifter guided in a bracket 65 on said valve shaft and adapted to be op-

erated by said pivot rod, and an air valve communicating with the engine cylinder and operated by said lifter.

5. In an internal combustion engine, a valve mechanism comprising a valve shaft, 70 a valve trip fixed upon said shaft, a push rod engaging said trip, means for operating said push rod synchronously with the stroke of the engine piston, means for sliding said valve shaft, an arm splined on said valve shaft and engaging the fuel valve of the engine, an auxiliary air valve mechanism comprising a lifter guided in a bracket on said valve shaft, and adapted to be operated by said push rod, and an air valve communicating 75 with the engine cylinder and operated by said lifter; and a reverse mechanism comprising an arm pivoted on said valve shaft and having one end engaging said lifter and the opposite end operated by said push rod 80 mechanism.

6. In an internal combustion engine, a valve mechanism comprising a bracket mounted upon the engine, a valve shaft 90 slideable in said bracket, means for adjustably sliding said shaft, a valve trip fixed upon said shaft having a head inclined transversely to the axis of said shaft, a sleeve on said shaft and having an arm, a fuel valve engaging said arm, a push rod engaging said 95 inclined head operated by the engine synchronously with the piston stroke and guided in an oscillatable sleeve mounted on the engine, and a scavaging valve operated by a lever linked to an arm on said oscillating sleeve.

7. In an internal combustion engine a valve mechanism comprising a bracket mounted upon the engine, a valve shaft slideable in said bracket, means for adjustably 105 sliding said shaft, a valve trip fixed upon said shaft having a head inclined to the axis of said shaft, a sleeve splined on said shaft and having an arm, a fuel valve engaging said arm, a push rod engaging said inclined head and guided in an oscillatable sleeve, an arm on said oscillatable sleeve, a connecting rod, a lever, a scavaging valve operated by said lever, and a rocker arm pivoted on the engine having one end engaging said push 110 rod, and the opposite end linked to the engine piston.

8. In an internal combustion engine a valve mechanism comprising a bracket mounted upon the engine, a valve shaft slideable in said bracket, means for adjustably 120 sliding said shaft, a valve trip fixed upon said shaft having a head inclined to the axis of said shaft, a sleeve splined on said shaft and having an arm, a fuel valve engaging said arm, a push rod engaging said inclined head and guided in an oscillatable sleeve, an arm on said oscillatable sleeve, a connecting rod, a lever, a scavaging valve operated by said lever, a rocker arm pivoted on the en- 125 130

gine having one end engaging said push rod, and the opposite end linked to the engine piston; a rocker cam pivoted on said valve shaft, a valve lifter guided in a bracket 5 mounted on said shaft and having a spring trip adapted to engage said push rod, a head on one end of said rocker cam engaging said lifter and a notch on said rocker arm, a lug on said connecting rod adapted 10 to engage said notch, an auxiliary air valve, and a pivoted lever engaging said air valve and said lifter.

9. In an internal combustion engine a valve mechanism comprising a bracket 15 mounted upon the engine, a valve shaft slideable in said bracket, means for adjustably sliding said shaft, a valve trip fixed upon said shaft having a head inclined to the axis of said shaft, a sleeve splined on said shaft 20 and having an arm, a fuel valve engaging said arm, a push rod engaging said inclined head and guided in an oscillatable sleeve; an arm on said oscillatable sleeve, a connecting

rod, a lever, a scavaging valve operated by said lever, a rocker arm pivoted on the engine having one end engaging said push rod and the opposite end linked to the engine piston; a rocker cam pivoted on said valve shaft, a valve lifter guided in a bracket mounted on shaft and having a spring trip 25 adapted to engage said push rod, a head on one end of said rocker cam engaging said lifter and a notch on said rocker arm, a lug on said connecting rod adapted to engage 30 said notch, an auxiliary air valve, a pivoted lever engaging said air valve, and said lifter, and means for manually operating 35 said auxiliary air valve.

In testimony whereof, I have hereunto set my hand at San Francisco, California, this 31st day of January 1913.

JOHN A. BROMAN.

In presence of—

BALDWIN VALE,
JAMES FITZGERALD.
